Primary Examiner — Wan Laymon(74) *Attorney, Agent, or Firm* — Griffin C. Klema; Peter Chiabotti(57) **CLAIM**

The ornamental design for a tattoo needle cartridge, as shown and described.

DESCRIPTION

FIG. 1 is a front top perspective view of a tattoo needle cartridge in accordance with the present disclosure; FIGS. 2 and 3 are side views thereof; FIG. 4 is a top view thereof; FIG. 5 is a bottom view thereof; FIG. 6 is a rear view thereof; FIG. 7 is a front view thereof; and, FIG. 8 is a side skewed perspective thereof. The features shown in broken lines in the various Figures are for illustrating environmental structure and form no part of the claimed design.
